John P. Ball,
Inventor,

UNITED STATES PATENT OFFICE.

JOHN P. BALL, OF CHICAGO, ILLINOIS.

CLEANSING APPARATUS.

Application filed November 9, 1922. Serial No. 599,944.

To all whom it may concern:

Be it known that I, JOHN P. BALL, a citizen of the United States, residing at No. 2514 East 73rd Place, in the city of Chicago, in the county of Cook and State of Illinois, United States of America, civil engineer, have invented certain new and useful Improvements in a Cleansing Apparatus, of which the following is a specification.

10 This invention relates to a cleansing apparatus more especially adapted for cleansing clothes and other textile material by utilizing a current of compressed air whereby a current of cleansing fluid is forcibly discharged onto the clothes or material to be cleaned; the fluid allowed to drain through the action of gravity from the clothes-containing vessel, after which a current of air is discharged into the vessel and 15 therefore into direct contact with the clothes or material; the introduction of the cleansing fluid and air currents being automatically accomplished in intermittent periods determined by regulable mechanism; the alternate action or introduction of cleansing fluid and air producing an efficient cleansing 20 action.

Another object of my invention is the provision of means whereby an independent 30 boiler or vessel may be arranged in communication with the cleansing chamber to permit a continuous heating process; while at the same time means are provided whereby the soapy material or suitable cleansing 35 fluid may be readily introduced into the heated water prior to its introduction into the clothes holding chamber or receptacle.

Another object of my invention is to provide a construction whereby the fouled or 40 soiled soapy foam, rising to the top of the clothes-holding chamber, may be forced or blown therefrom, through the action of the air currents, and discharged from said clothes-holding vessel into a precipitate collecting receptacle.

45 The apparatus for practicing my invention may have different form, adapting it to various kinds of material and while I show the preferred form in the accompanying drawings, I do not confine myself to the specific form illustrated.

In the drawings:—

50 Figure 1 shows a cross-sectional view of the apparatus and an air compressor engine,

represented by I, an air compressor reservoir I², and air pipes I³, this drawing is presented in order to show the connection of the source of air supply with the details of this invention.

55 Figures 2 and 3 are detail sectional views of valve mechanism and controlling means, with the valve and mechanism shown in alternate positions.

Figure 4 is a top plan view with portions broken away and shown in section.

60 In the specific exemplification of the invention as disclosed in the drawings, it comprises a perforated and preferably cylindrical vessel shown at A, adapted to receive the clothes or material to be operated on; the vessel A being preferably free to revolve on the vertical spindle B. The vessel A is made of foraminated material, preferably suitable wire mesh, to permit the cleansing fluid to readily enter and discharge therefrom. 65 The clothes-container or vessel A is enclosed by a cylindrical housing C preferably having a removable top H provided with a central opening which is preferably flared outwardly as shown at D and through which the spindle B extends. The housing C is also provided with openings in the bottom K to receive suitable nozzles as shown at E and E'. The housing C in turn is surrounded by a precipitate collecting receptacle F, whose bottom may constitute the bottom of the housing C as shown in Figure 70 75 80 85 90 95 100 105 110 115 120 125 130 - ranged in juxtaposition to the vertical axis of the apparatus. These conduits terminate in truncated conical upper ends or nozzles as shown at E and E'. The conduits 5 Q and Q', at a point intermediate of the reservoir L and the bottom of the housing or receptacle C are formed to provide a suitable slide-way for a slide-valve N which is adapted to alternately control the two 10 conduits Q and Q'. These conduits Q and Q' are also formed to receive the ends of suitable air conveying conduits or pipes O and P and O' and P', respectively; that is to say, the conduit Q is shown provided 15 with an air pipe O entering through the side wall thereof at a point above slide-valve N and with the pipe P entering through the side wall of the conduit at a point beneath the valve N; while conduit 20 Q' is provided with the air pipe O' disposed through the side wall thereof at a point above the slide-way of the valve N and with the air pipe P' disposed through the side wall at a point beneath the slide-way 25 of valve N. The air pipes O and O' are preferably provided with upwardly disposed ends or jets T and T', respectively, arranged axially within the conduits Q and Q'; while the pipes P and P' are likewise provided with upwardly disposed ends or jets U and U', respectively, disposed axially within conduits Q and Q', but at 30 points beneath the slide-way for the valve N.
- 35 The mechanism for controlling the slide-valve is shown at M, preferably in the nature of a cylinder provided with a reciprocating piston which is preferably operated by compressed air obtained from an 40 air presser or suitable source of air supply; although steam or other motive power may be used.
- 45 Each air supply pipe O, O' and P, P' is provided with a suitable valve, preferably of a type which normally remains in closed position, by any suitable means, and which are each provided with engaging portions, as shown at R, R' and S, S'. The flow of air through the pipes is normally 50 shut off until the respective valves are opened by means of strikers secured to the plunger or rod X which controls the slide-valve N; the strikers being indicated at V and W, whereby the valve operating means R and 55 S are actuated, and strikers V' and W', whereby the valve operating means R' and S' are actuated. The plunger or rod X may be operated in any suitable manner, as for example by means of the connecting 60 link and piston of the driving mechanism M which actuates the rotating wrist-plate or wheel to which the plunger or rod X is eccentrically and pivotally connected as shown in Figure 1. This will cause the 65 slide-valve N to be reciprocated so as to alternate close off conduit Q as shown in Figures 1 and 2 and conduit Q' as shown in Figures 3 and 4. With this construction, namely with the striker members arranged on the plunger or rod and an extension of valve N as shown in the drawings, valve operating means R in air pipe O and valve operating means S' in air pipe P' are moved to open position when valve N has closed off conduit Q, as shown 70 in Figures 1 and 2; while reciprocation of the slide-valve N to the right in Figure 1, namely so as to close off conduit Q' and open conduit Q will cause striker W to actuate valve operating means S in conduit P and striker V' to actuate valve operating means R' in air pipe O', at which time the valve in air-pipe O and the valve in air-pipe P' will be closed. The tank L may be supplied with a cleansing fluid 75 such as soapy water, gasoline or naphtha through a supply pipe Y controlled by a suitable hand-valve as shown and if the tank L is charged with water it may be heated in any suitable manner as for example by means of a gas-burner and gas supply conduit shown at Z located beneath tank L.
- 80 With the construction illustrated, compressed air is introduced into the conduits Q, Q' through the operation of the valves as heretofore described; while the conduit which has been opened through movement of the valve N will also have the cleansing fluid flow upwardly therethrough by reason 85 of the suction caused by the air current or blast; the cleansing fluid being caused to pass through the bottom of the clothes-containing receptacle A. With the mechanism in the condition illustrated in Figure 1, 90 where valve S' is held open so as to have a blast of air issue from jet U', the cleansing fluid will be caused to pass upward through conduit Q' and introduced into vessel A and upon the reciprocation of valve N to the 95 right in Figure 1, the valve controlled by means S' will return to closed position, at which time the valve in air-pipe P will be 100 opened and the cleansing fluid made to flow upwardly through conduit Q. While the 105 cleansing fluid is forced through one conduit into the clothes holding receptacle, a blast of air is being injected through the upper air pipe in the other conduit and this air blast will cause the soiled foam or suds 110 to be blown upwardly and out through the opening D in the receptacle C, thereby removing a considerable portion of the dirt laden suds or foam.
- 115 In the washing of clothes and other material, it is desirous to effect a complete diffusion of soapy material into the cleansing liquid. My invention provides a liquid soap supply pipe T' entering the air supply pipe, 120 and the supply of soap may be regulated by 125

a hand valve as at t' , the liquid soap being supplied under air pressure.

What I claim is:—

1. In an apparatus of the character described, the combination of a plurality of containers arranged in superposed relation, the upper container being provided with foraminated walls and adapted to constitute a clothes-holding container while the lower 10 container is adapted to be provided with a cleansing fluid, means for effecting communication between the cleansing fluid container and the lower part of the clothes-holding container, a compressed air supply 15 having communication with said means, and means whereby a current of compressed air and cleansing fluid and a separate current of compressed air are alternately passed through said first mentioned means into the 20 lower part of the clothes-holding container.

2. In an apparatus of the character described, the combination of a plurality of containers, one of said containers constituting a cleansing fluid holding chamber, the 25 other containers being disposed above the cleansing fluid container and arranged one within the other, with the inner container constituting a clothes-holding container provided with a foraminated bottom and an 30 open top, a pair of conduits leading from the cleansing fluid container into the bottom of one of the upper containers and beneath the foraminated bottom of the clothes-holding container, a source of compressed air 35 supply, air lines leading from the source of compressed air supply into each of said conduits and opening upwardly therein whereby the cleansing fluid is caused to flow upward through the conduits when certain of the air lines are open, and means 40 whereby the conduits are alternately placed in open and closed condition and flow through the air-lines controlled.

3. In apparatus of the character described, a foraminated clothes holding receptacle, a collecting chamber in which the receptacle is mounted, a cleansing fluid holding chamber, a plurality of conduits leading from the last chamber to the bottom of the 50 receptacle, means whereby said conduits are successively opened and closed, a source of compressed air, a pair of air pipes leading from the compressed air supply into each conduit on opposite sides of said means, 55 and means on said first means and said air pipes whereby the air pipe disposed above the first means in one conduit and the air pipe disposed below the first means in a second conduit are placed in air admitting 60 condition when said first means is in one position and the other air-pipes placed in air admitting condition when said first means has moved to a second position.

4. In apparatus of the character described, a clothes holding receptacle, a sepa-

rate cleansing fluid holding chamber, a plurality of conduits for conveying the cleansing fluid from said chamber to said receptacle, means whereby said conduits are successively opened and closed, a source of compressed air, a pair of air pipes leading from the compressed air supply to each conduit on opposite sides of said means, and means on said first named means and said air pipes whereby the air pipe disposed on one side 75 of the first means in one conduit and the air pipe disposed on the other side of the first means in a second conduit are placed in air admitting condition when said first means is in one position and the other air-pipes placed in air admitting condition when said first means is in a second position.

5. In apparatus of the character described, a foraminated clothes holding receptacle, a cleansing fluid holding chamber disposed beneath the receptacle, a pair of conduits leading from the fluid holding chamber and terminating in discharge nozzles beneath the receptacle, means whereby the conduits are successively opened and closed, a source of compressed air, a pair of air pipes leading from the compressed air supply into each conduit above and below said means, and means on said air pipes operable by said first means whereby the air pipe above the first means in one conduit and the air pipe below the first means in the second conduit are placed in air admitting condition while the other air pipes are closed when the first means is in one position and vice versa when said first means has moved to a second position.

6. In apparatus of the character described, a clothes holding receptacle, a separate cleansing fluid holding chamber, a plurality of conduits for conveying the cleansing fluid from said chamber and terminating in discharge nozzles at the bottom of said receptacle, a slide-valve adapted to control said conduits so as to permit flow of cleansing fluid through one conduit while the other conduit is closed, a source of compressed air, a pair of air pipes leading from the compressed air supply to each conduit above and below said slide-valve, means whereby the flow of air through said pipes is controlled, and means whereby the slide-valve is reciprocated, the conduits alternately placed in open and closed condition 110 and the first means actuated so as to admit air above the slide-valve in one conduit and below the path of the slide-valve in the other conduit when the slide-valve is in one position and vice versa when the slide-valve is in a second position.

7. In apparatus of the character described, a clothes holding receptacle, a cleansing fluid holding chamber disposed below said receptacle, a collecting chamber 130

- disposed about said receptacle, injector means adapted to raise the cleansing fluid from the holding chamber and to discharge same into said receptacle, means for controlling operation of the injector means, and means whereby a separate current of compressed air is discharged into the receptacle when the injector means is shut off.
- 10 8. In apparatus of the character described, a clothes holding receptacle, a cleansing fluid supply container, conduits leading from the supply container to said receptacle, a source of compressed air, means for conveying compressed air into said conduits whereby the cleansing fluid may be siphoned into said conduits and injected into said receptacle, and means whereby flow

of the cleansing fluid through said conduits may be controlled.

9. In apparatus of the character described, a clothes holding receptacle, a cleansing fluid supply, a compressed air supply, means communicating with said fluid supply and said air supply, adapted to inject the fluid and the compressed air into the receptacle, and means for controlling the first means so as to provide alternate injections of fluid and air into the receptacle.
